UNITED STATES PATENT OFFICE.

FROST V. SIMPSON, OF MILWAUKEE, WISCONSIN, ASSIGNEE TO KIECKHEFER BOX COMPANY, OF MILWAUKEE, WISCONSIN, A CORPORATION OF WISCONSIN.

YIELDING PLATEN CONNECTION.

1,393,934.

Specification of Letters Patent. Patented Aug. 8, 1916.

Application filed December 7, 1914. Serial No. 875,746.

To all whom it may concern: Be it known that I, FROST V. SIMPSON, a citizen of the United States, and resident of Milwaukee, in the county of Milwaukee and State of Wisconsin, have invented new and useful Improvements in Yielding Platen Connections, of which the following is a description, reference being had to the accompanying drawings, which are a part of this specification.

This invention has for its object to provide a platen connection for presses for clamping the glued flaps of fiber boxes and the like while forming the box, the connection being so constructed as to permit of a rocking movement of the platen to apply an even pressure to all parts of the box, notwithstanding a difference in thickness thereof, and also being adapted to yield slightly under spring pressure to permit of the desired clamping action without readjustment when changing from material of one thickness to material of another thickness.

With the above and other objects in view the invention consists in the yielding platen connection as herein claimed and all equivalents.

Referring to the accompanying drawings in which like characters of reference indicate the same parts in the different views: Figure 1 is a side elevation of a box forming press having a platen connection constructed in accordance with this invention; Fig. 2 is an enlarged sectional detail view thereof; and, 35 Fig. 3 is a sectional view on the plane of line 3—3 of Fig. 2.

In these drawings 10 indicates a plunger which is suitably mounted in a stationary frame 11 and is operated by a cam lever 12 40 while a platen 13 carried by a tubular stem 14 in a pivotally mounted socket 15 cooperates therewith to press between them the glued flaps of a fiber box 16 or the like as with the press covered in my co-pending application Serial No. 847,918, filed June 29, 1914.

The present invention relates to the connection between the platen 13 and the swinging tubular stem 14 on which it is mounted. 50 A shouldered bushing 17 is fitted in the upper end of the tubular stem 14 and is rigidly held in place by a set screw 18. A sliding pin 19 loosely fits within the bore of the

bushing 17 with a coil spring 20 surrounding it and bearing at its upper end against an enlarged head of the pin and at its lower end against the bushing 17 to hold the pin normally in its uppermost position with spring pressure. The pin 19 is prevented from being withdrawn from the bushing 17 under the action of its spring 20 by a cross pin 21 passing through its lower end and engaging the bottom of the bushing 17. The pin 19 is furthermore prevented from turning within the bushing 17 by having a key 22 therein fitting in a longitudinal keyway in the bushing 17. The platen 13 has an annular flange 23 on the bottom thereof surrounding the head of pin 19 and the upper end of the head of pin 19 is convex to form a spherical bearing surface 24 upon which the platen rests. By reason of the convex formation of the bearing surface of the pin 19 on which the platen rests and by reason of the fact that the flange 23 is of larger internal diameter than the head of the pin the platen is capable of tilting slightly in any direction. In order that the platen may not turn on the head of pin 19 a set screw 25 is threaded in the flange 23 with its reduced end engaging one of a number of openings 26 in the side of the head. The purpose of preventing the turning of the platen on the head of pin 19 and of preventing the turning of the pin is to maintain registration of the rectangular platen with the correspondingly shaped plunger 10, as is made necessary by the provision of guide lugs 27 at one edge of the plunger 10 which assist in truing the box at the time of applying pressure thereto. The reduced end of the set screw 25 is sufficiently smaller than the openings 26 to permit of the slight tilting movements of the platen in any direction, and by removing said set screw and turning the stem 14 in its thread connection with the socket 15 an adjustment of the elevation of the platen is obtained for accommodating work of different thickness.

By means of the platen connection of this invention the platen of a box forming press may readily adapt itself to a variation in thickness of the material so as to apply equal pressure at all parts of the overlapping flaps of the box, and furthermore the yielding of the platen under spring pressure enables

the press to be operated with material of different thickness without requiring a change in adjustment thereof.

The platen stem 14 is shown mounted in the socket 15 and this structure is pivoted upon the pin 28. This pin 28 is carried in the foot or base plate 29 upon which the whole device stands. The socket 15 has a rearwardly extending bracket 30 carrying an adjusting screw, and also has a forwardly extending toe 32. In the normal aligned position of the platens 13 and 10 as shown in Fig. 1, the socket is carried by the pin 28 and the adjustment screw 31. When it is desired to insert or remove a box 16, then the stem 14 and the socket 15 are swung clockwise about the pin 28 until the toe 32 engages the base plate 29. In this position the platens 13 and 10 are disaligned and the box with its one end sealed may be removed and another which it is desired to seal put in its place. Thereupon the stem 14 is swung contra-clockwise to again align the plunger so that the box flaps which have been provided with paste may be sealed together.

What I claim as new and desire to secure by Letters Patent is:

1. In a box forming press, a platen having a socket on the bottom thereof, and a platen supporting member loosely fitting in the socket and having a spherically rounded bearing surface at its end engaging the bottom of the platen to permit the platen to rock in any direction, said socket having a substantially flat bearing surface for engaging the rounded extremity of said member.
2. In a box forming press, a platen having a socket on the bottom thereof, a platen supporting member loosely fitting in the socket and having a spherical rounded bearing surface at its end engaging the bottom of the platen to permit the platen to rock in any direction, said socket having a substantially flat bearing surface for engaging the rounded extremity of said member, and a set screw threaded in the socket and engaging an opening in the side of the platen supporting member.
3. A platen connection for box forming presses, comprising a slidably mounted spring pressed pin having a rounded bearing surface for tiltably supporting the platen

and a slidable support for said pin adapted through the agency of said spring to take 55 the thrust from said platen.

4. In a box press or the like, a platen having a socket formed on the bottom thereof, a platen supporting stem, a spring pressed pin tiltably mounted in the platen 60 supporting stem and having a head fitting in the socket of the platen with a rounded bearing surface between the head of the pin and the bottom of the platen to permit the platen to rock and a slidable support for 65 said pin adapted through the agency of said spring to take the thrust from said platen.

5. In a press for forming paper boxes and the like, a platen having a socket formed 70 on the bottom thereof, a platen supporting stem having a threaded connection for longitudinal adjustments, a shouldered bushing fitting in the platen supporting stem, means for preventing the bushing from turning 75 within the platen supporting stem, a headed pin slidably mounted in the bushing, a key for preventing the turning of the pin in the bushing, a coil spring surrounding the pin and engaging the head of the pin and the 80 bushing respectively, the head of the pin fitting within the socket of the platen and having a spherically rounded bearing surface to permit the platen to rock in any direction, and a set screw threaded in the 85 socket and loosely engaging an opening in the head of the pin to prevent the platen turning on the pin.

6. In a device of the character described the combination with two platens, means 90 whereby said platens are moved into and out of parallel aligned relation, means for moving said platens relatively toward and away from each other when in their aligned condition, and a stem for supporting one of 95 said platens having a rounded upper bearing surface and said platen having a co-operating substantially flat bearing surface to engage the said stem.

In testimony whereof, I affix my signature, in presence of two witnesses.

FROST V. SIMPSON.
